TYPOGRAPHICAL MACHINE

Clay E. Murray, near Davenport, Iowa, assignor
to Linograph Corporation, Davenport, Iowa, a
corporation of Delaware

Application February 4, 1939, Serial No. 254,699

20 Claims. (Cl. 199—42)

My present invention relates to typographical machines and more particularly to the distributor mechanism thereof. Among the objects of this invention are to provide, in a machine of the character indicated, an improved distributor mechanism; to provide, in a machine of the character indicated, means whereby the operator may shift the machine from one rate of distributing matrices to another, almost instantly; to provide in a typographical machine for the raising of one of the feed screws so that access may be had to the distributor bar and the returning of said screw to distributing position without disturbing the relationship of the threads of the feed screws to each other; to provide an improved actuating mechanism for the matrix lifting mechanism in a machine of the character described; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof:

30 Fig. 1 represents a broken fragmentary elevation of a machine embodying my present invention;

35 Fig. 2 represents a view similar to Fig. 1 but with some of the parts in a different adjusted position;

Fig. 3 represents a side elevation of the structure shown in Figs. 1 and 2;

40 Figs. 4 and 5 represent fragmentary transverse sections taken substantially along the plane indicated by the line 4—4, Figs. 2 and 7;

Fig. 6 represents a fragmentary transverse section taken approximately along the plane indicated by the line 6—6, Fig. 2;

45 Fig. 7 represents a vertical longitudinal section of the upper right hand portion of the structure shown in Fig. 1;

Fig. 8 represents an end elevation of the structure shown in Fig. 7, looking in the direction of the arrows 8 on line 8—8;

50 Fig. 9 represents a fragmentary front elevation, partly broken away, of a part of the machine shown at the left hand end of Figs. 1 and 2.

Reference will now be made in greater detail to the annexed drawings for a more complete description of this invention. In these drawings,

the frame of the machine is indicated by the numeral 1, only fragments thereof being illustrated. As is well known in the art, it is common practice to support the matrices upon a section 2 and, by suitable means, transfer them to a point where they can be lifted to the distributor bar 3. It is not regarded as necessary to illustrate or describe the mode of getting the matrices on the section 2, inasmuch as it is well known by those familiar with the art. Lifting of the 10 matrices into position to be entered upon the section 3 of the distributor bar is illustrated in a number of patents, some of which are Rogers, 942,845; Converse, 942,848; and Rogers, 1,057,455.

The lower feed screw is indicated at 4 and 15 one of the upper feed screws at 5. On the right hand end of the screw 4 is a gear 6, while the corresponding end of the screw back of screw 5 has a gear 7 secured thereto. These gears are connected in cooperative relation by means of a 20 gear 8 mounted on a drive shaft 33 of the machine. A clutch is indicated, generically, in connection with gear 6, by the numeral 6a. A gear 9 is formed on or secured to the outer cylindrical surface of a circular or ring cam member 10 of 25 generally cup-shaped form. The bottom 11 of this cup has a sleeve 12 projecting therefrom which is mounted in a bracket 13 secured to the frame 1 in any suitable manner, as, for example, by a bolt 14. It will be understood that, since 30 the gear 9 rotates, the sleeve 12 must also rotate. A plunger 15 is slidably mounted within the interior of the ring cam member 10, said plunger having an arm 16 extending through the sleeve 12 and into a position to be engaged by an 35 adjustable member 17 carried by the upper end 18 of a lever 19. This lever is pivoted at 20 upon a part 21 of the machine frame 1. The lower end of the lever 19 is provided with a finger piece 22 which carries a latching member, indicated at 23, 40 which latching member cooperates with either of a plurality of depressions or holes 24 in the lower end of part 21 of the frame. As shown in Fig. 3 of the drawings, the lower end portion of the lever 19 has a socket formed therein, and this 45 socket contains a spring-pressed ball to engage in the openings 24 and hold the lever 19 in adjusted position.

A semicircular projection 25 upon the face of the plunger 15 serves as a bridging member between two cam crests 26 and 27. Between these cam crests are depressions 28 and 29, the purpose of which is apparent. When the lever 19 is turned about its pivot 20 to the position shown in Fig. 1, the arm 16 and plunger 15 are forced 50 55

to the left, as shown in Figs. 1 and 7. In this position, the projection 25 bridges the space between the cam crests 26 and 27 so that the depression 28 is ineffective in permitting the rod 30 to move to the right. However, as the gear 9 and circular cam 10 turn through 180°, the cam depression 29 permits the rod 30 to move to the right, as will be perfectly obvious. It will of course be understood that the projection 25 may 10 take the form of a semicircular ring projecting from the face of the plunger 15, the projection being of sufficient width to serve as a track for the roller 51. Power is supplied through a belt 31 to a belt pulley 32 on the shaft 33 and from 15 the pulley 32 through shaft 33 to gear 3. From this, power is transmitted to gears 6 and 7 and the remainder of the gear train driving the distributing screws. As shown in Figs. 1, 2, and 4, a gear 7a, on the shaft of screw 5, is directly in 20 front of the gear 7 and hides the same from view. This gear 7a meshes with the gear 9 and has the same number of teeth as the gears 6 and 7. The gear 9 has, preferably, twice the number of teeth of the gears 6, 7, and 7a. A gear 8a connects the 25 gears 7 and 9 in driving relation and, together, the gears 6, 7, 7a, 8, 8a, and 9 constitute a gear train, the gears of which are constantly in mesh, whether they are in the position illustrated in Fig. 4, that illustrated in Fig. 5, or in any intermediate position. The purpose of this will be 30 described presently.

At the left side of the machine a pair of arms 34 and 35, constituting a compound lever, are mounted upon a pivot member 36 and are capable of having their relative positions adjusted by means of the screw 37. These two arms 34 and 35 are connected by means of a spring 38 which normally holds them in a fixed position with relation to each other. A spring 39, connected to the distributor box 40 and to the arm 34, normally pulls this latter as far to the right as the rod 30 will permit it to go. A finger 41, pivoted at 42 upon the arm 35 (see Fig. 9), is pressed by a spring 43 against a stop 44 mounted between two arms 45 projecting from a corner of the distributing box 40. An abutment member 46 has a socket formed therein for the reception of one end of the spring 43, and the spring therefore presses constantly against the finger 41 to hold it against the stop member 44. A pair of parallel arms 47 and 48 project toward the right from the box 40 and serve to guide the matrices as they are moved forwardly from the bar 2 to be entered upon the bar 3. As the matrices drop from the bar 3, they collect in proper compartments in the magazines 50. However, this is disclosed sufficiently in prior patents that it is not necessary to go farther into the details of this construction.

From the foregoing it will be understood that as the roller 51, mounted in the forked end of rod 30, rides along the edge of the cam 10, the rod will be caused to reciprocate under the influence of the cam and the spring 39. It will also be understood that, as the lever 19 is moved from the position illustrated in Fig. 2 to that illustrated in Fig. 1, the plunger 15, carrying the semicircular enlargement 25, will be moved to the position illustrated in Fig. 7, thus bridging the gap between the two crests 26 and 27. This reduces the number of reciprocations of the rod 30 for each rotation of the gear 9. As illustrated, the cam 10 is constructed to cause two complete reciprocations for each rotation of the gear 9. Therefore, the setting illustrated in Fig. 1 reduces the number of reciprocations of the rod 30 from

two to one for each rotation of the gear. Since the gear 9 has twice as many teeth as the gears 6, 7, and 7a, the rod 30 will reciprocate once for each rotation of the feeding screws 4 and 5, if the lever 19 is set as illustrated in Fig. 2. On the other hand, if the lever is set as shown in Fig. 1, the rod 30 will reciprocate once for each two turns of the feeding screws. Therefore, the finger 41, which causes lifting of the matrices, may be easily made to lift the matrices for each turn of the distributing screws or for every other turn thereof. Hence, if the matrices are thin, the lever 19 may be set as illustrated in Fig. 2, and the matrices will be distributed rapidly. On the other hand, if a series of thick matrices are encountered, the lever 19 may be quickly adjusted to the position shown in Fig. 1, and then the matrices will be distributed only half as fast and will not interfere with each other as they are liable to do if an attempt be made to distribute a thick matrix for each turn of the distributing screws.

Brackets 53 are mounted on the frame 1 and support a shaft 54 pivotally therein. At the ends of the shaft 54 are arms 55 and 56 which support the two end portions of the distributing screw 5. A spring hook 57 extends through an opening in the arm 55 and latches against the front side thereof to tightly hold the arms 55 and 56 and the screw 5 in position, as illustrated in Figs. 1, 2, 4, and 6. However, by pressing upwardly upon the end of the spring 57, the arm 55 may be unlatched and the screw 5 raised to the position shown in Fig. 5 or anywhere between that position and the position shown in Fig. 4.

A brake 58 is pivoted at 59 and actuated into 35 braking position by means of a spring 60. The free end of this braking member is engaged by a bar which is pivotally mounted on the frame 1 and extends transversely of the machine as is well understood by those familiar with machines of 40 this type. When this crossbar is unlatched and lifted, the brake member 58 is actuated by the spring 60 about its pivot 59 and engages the collar 61 to put a braking force upon the shaft of the screw 4, thus preventing rotation thereof. 45 A thrust bearing 62 surrounds the arm 16 between the members 11 and 13 and reduces to a minimum the friction between these members, due to pressure by the rod 30 against the cam 10.

From the foregoing description, taken in connection with the annexed drawings, it will be seen that I have provided a simple and easily manipulated means for changing the rate of distribution of matrices in a machine of the character described. Also, it will be observed that I 55 have provided a structure which is so arranged that it is impossible for the distributing screws to get out of properly timed relationship when the movable one thereof is raised to enable the operator to get at the matrices between the distributing screws, in event it should be desirable for any reason to get at such a matrix or matrices.

It will of course be understood that the specific description of the structure set forth above may be departed from without departing from the 65 spirit of my invention as set forth in this specification and the appended claims.

Having now described my invention, I claim:

1. In a typographical machine, a distributing mechanism comprising a plurality of matrix feeding screws, mechanism for feeding matrices, one at a time, to said screws, and mechanism for actuating the second mentioned mechanism whereby to selectively cause said second mentioned mechanism to be actuated either once for 75

each rotation of said screws or once for each two rotations of the screws.

2. In a typographical machine, a distributing mechanism comprising a plurality of matrix feeding screws, a gear train connecting said screws to cause them to rotate at the same rate, one of the gears of said gear train having a cam connected thereto to cause feeding of matrices to said feeding screws, said cam having a plurality of cam surfaces to cause feeding of a matrix to each thread of the feeding screws, and a bridging means movable into a position to reduce the number of effective cam surfaces causing feeding of matrices to said screws whereby to reduce the number of matrices delivered per rotation of the screws.

3. In a typographical machine, a distributing mechanism comprising a plurality of matrix feeding screws, a gear train connecting said screws to cause them to rotate at the same rate, one of the gears of said gear train having a cam connected thereto to cause feeding of matrices to said feeding screws, said cam having a plurality of equally spaced depressions between cam crests, and an actuating rod cooperating with said cam to cause feeding of matrices to said screws.

4. In a typographical machine, a distributing mechanism comprising a plurality of matrix feeding screws, a gear train connecting said screws to cause them to rotate at the same rate, one of the gears of said gear train having a cam connected thereto to cause feeding of matrices to said feeding screws, said cam having a plurality of equally spaced depressions between cam crests, an actuating rod cooperating with said cam to cause feeding of matrices to said screws, and a reciprocable block to bridge one of the depressions between cam crests whereby to reduce the number of actuations of the rod per rotation of said one of said gears.

5. In a typographical machine having feeding screws for matrices, an actuating arm for feeding the matrices to the screws, and a rod for actuating said arm; the combination of gears for rotating the screws, a cam mounted on one of said gears and rotating therewith, said cam having a pair of crests and intermediate depressions for actuating said rod whereby to cause feeding of the matrices, and mechanism whereby one of said depressions is bridged so that one of said cams is rendered ineffective to cause actuation of said rod.

6. In a typographical machine, a distributing mechanism for matrices, comprising a reciprocating rod for causing lifting of the matrices into position to be distributed, a rotating gear for causing distributing movement of the matrices, said gear having means thereon for causing two complete reciprocations of said rod for each complete rotation of said gear, and means in conjunction with the last named means for causing reduction in the number of reciprocations of said rod per rotation of said gear.

7. In a typographical machine having a frame and a plurality of feed screws for causing distributing movement of matrices; a shaft pivotally mounted on said frame, brackets carried by said shaft and having one of said screws rotatably mounted therein, and a gear train connecting said screws in cooperative relation, said gear train including as a part thereof a driving gear, the gear on the screw carried by said brackets meshing continuously with the driving gear both during feeding movement of the screws and when

the brackets are moved to carry said screw carried thereby about said shaft whereby to expose the matrix distributor bar.

8. In a typographical machine having a plurality of feed screws, means for distributing matrices to said screws and gears for rotating said screws; the combination of a circular cam provided with a plurality of cam surfaces, an actuating rod for actuating matrices into distributing position, said cam cooperating with said rod in causing movement of the matrices, and reciprocable means cooperating with said cam to make part of said cam surfaces temporarily inoperative to cause actuating movement of said rod.

9. A structure as defined by claim 8 in which the last named means has a stem projecting longitudinally therefrom through the bearing for the cam whereby to make possible the application of force to said reciprocable means to cause reciprocating movement thereof.

10. In a typographical machine having a plurality of feed screws, means for distributing matrices to said screws and gears for rotating said screws; the combination of a circular cam provided with a plurality of cam surfaces, an actuating rod for actuating matrices into distributing position, said cam cooperating with said rod in causing movement of the matrices, reciprocating means cooperating with said cam to make part of said cam surfaces temporarily inoperative to cause actuating movement of said rod, the reciprocable means having a stem projecting longitudinally therefrom through the bearing for the cam whereby to make possible the application of force to said reciprocable means to cause reciprocation thereof, and a manually operated lever on the frame of the machine to move said reciprocable means in one direction.

11. In a typographical machine having a plurality of feed screws for matrices to be distributed, a gear train connecting said screws in cooperative relation, one of the gears of said gear train having twice as many teeth as the gears with which it meshes, a hollow cam member extending from a face of the larger gear coaxially therewith, said cam member having two cam crests and intervening cam depressions, a reciprocable bridging member in the hollow of said cam member to bridge the gap between two cam crests whereby to reduce to one the number of effective cam surfaces of said cam member, and actuating means for the matrices having operative connection to said cam member whereby the latter may cause the matrices to be fed to said feed screws.

12. In a matrix distributing machine, a supporting frame, a distributing box connected therewith, a plurality of feed screws supported by the frame in a position to have matrices fed thereto from said box, a gear train connecting said screws in timed relation, and means releasably holding one of said screws in feeding position, said gear train including a gear mounted on the end of said one of said screws, and a gear in mesh therewith, said one of said screws being movable about the axis of the second mentioned gear into a non-operative position to allow access to the other screws, the gears of the gear train continuously meshing and constantly maintaining the screws in timed relation and not permitting any of them to get out of such relation when said one of the screws is swung out of operative location.

13. In a typographical machine, a distributing box, distributing screws arranged in parallelism and receiving matrices from the distributing box, one of said screws being mounted to be moved away from and toward the others and, when being so moved, to be maintained in parallelism therewith, and a gear train constantly maintaining said screws in synchronous driving relation whereby to prevent them from getting out of timed relation when the one screw is moved away from the others.
14. In a typographical machine having distributing screws, a gear train for synchronously rotating said screws and maintaining them in constant cooperative driving relation, one of said screws being movable toward and away from the others but being always maintained in the same operative relation to the others.
15. In a typographical machine, a distributor box, matrix distributor screws associated and cooperating therewith, a compound lever on the box, a matrix lifting finger carried thereby and cooperating with the screws in distributing matrices, an actuator rod having one of its ends engaging said lever and actuating the same to cause matrices to be fed to said screws, a driving gear adjacent the second end of said rod, a ring cam on said gear presenting its cam edge toward said rod, said cam having alternating crests and depressions to cause reciprocation of the rod whereby to cause feeding of the matrices to the screws.
16. A structure as defined by claim 15 having a plug in said ring cam which may be moved axially to bridge part of the depressions between the crests whereby to reduce the number of actuations of said rod by said cam, per rotation of said gear.
17. Actuating means for a matrix lifter comprising a compound lever carrying the lifting finger at one end, a slidable rod engaging at one end of the second end of said lever, resilient means for turning one arm of said lever in one direction about its pivot to move said rod in one direction, a rotatable circular cam engaging the second end of said rod to move it in the opposite direction, said cam having a plurality of crests and depressions, and bridging means for bridging one of said depressions whereby to reduce the number of reciprocations of the rod per rotation of the cam.
18. A structure as defined by claim 17 having manually moved means for moving the bridging means into bridging position.
19. A structure as defined by claim 17 provided with a lever mounted on the machine frame adjacent the cam and within easy reach of the machine operator, the bridging means having an arm projecting therefrom toward said lever, and the lever engaging the arm to actuate the bridging member into bridging position when the lever is moved for that purpose.
20. In a typographical machine, a distributor box, matrix distributor screws associated and cooperating therewith, a compound lever on the box, a matrix lifting finger carried thereby and cooperating with the screws in distributing matrices, an actuator rod having one of its ends engaging said lever and actuating the same to cause matrices to be fed to said screws, a driving gear adjacent the second end of said rod, a ring cam on said gear presenting its cam edge toward said rod, said cam having alternating crests and depressions to be engaged by said rod to cause reciprocation of the rod whereby to cause feeding of the matrices to the screws, a shaft coaxial with said gear and pivotally mounted on the machine frame, arms carried by said shaft and swinging therewith about the axis thereof, one of the distributor screws being carried by said arms, a gear carried by said one of the distributor screws adjacent said driving gear and in mesh therewith, said two gears remaining constantly in mesh when said screw is moved about said shaft, other gears connected in driving relation to the other distributing screws and forming part of a gear train whereby said screws are rotated in timed relation, all of said gears being kept in mesh regardless of the position of said one screw with relation to said shaft, and a plug slidable in the hollow of the ring cam and serving to bridge part of the depressions therein whereby to vary the number of actuations of said rod by said cam, per rotation of said gear.

CLAY E. MURRAY.
